UNITED STATES PATENT OFFICE.

JOHN A. HELLWIG, OF ALBANY, NEW YORK.

BILL-FOLD.

1,073,120.

Specification of Letters Patent. Patented Sept. 16, 1913.

Application filed March 19, 1913. Serial No. 755,490.

To all whom it may concern:

Be it known that I, JOHN A. HELLWIG, citizen of the United States, residing at Albany, in the county of Albany and State 5 of New York, have invented certain new and useful Improvements in Bill-Folds, of which the following is a specification, reference being had to the accompanying drawings.

10 This invention relates to an improved bill fold and has for its primary object to provide a device of this character which is entirely constructed of aluminum or other sheet metal whereby the same will be extremely strong and durable, light in weight, 15 neat in appearance and may be manufactured and sold at comparatively small cost.

Another and more specific object of the invention resides in the provision of a bill 20 fold consisting of a plurality of hingedly connected sheet metal plates or leaves, and means for compactly folding the bills between the same when said leaves are arranged in relative superposed positions.

25 Still another object of the invention resides in the provision of improved means for attaching the bills at one of their ends to the central or intermediate leaf or plate.

A further object of the invention resides 30 in the provision of improved means for fastening and retaining the several hingedly connected leaves in their folded or superposed positions.

With the above and other objects in view 35 as will become apparent as the description proceeds, the invention consists in certain constructions, combinations and arrangements of the parts that I shall hereinafter fully describe and claim.

40 For a full understanding of the invention, reference is to be had to the following description and accompanying drawings, in which—

Figure 1 is a perspective view of my improved bill fold showing the same open; Fig. 2 is a section taken on the line 2—2 of Fig. 1; Fig. 3 is a perspective view of the bill fold closed; and Fig. 4 is a section taken on the line 4—4 of Fig. 3.

45 Referring in detail to the drawings, 5 designates the central plate or leaf, and 6 and 7 respectively designate the end plates. The opposite edges of the central plate 5 are curved or bent in the same general direction. 55 as indicated at 8 while the opposed edges of the end plates 6 and 7 respectively are bent

or curved in a relatively opposite direction to the curved edge of the central or intermediate plate 5 as indicated at 9. These several plates are connected by means of the 60 hinges 10, said hinges comprising a plurality of knuckles mounted upon a common pintle, said knuckles projecting beyond the outer faces of said plates. The several metal plates 5, 6 and 7 which constitute the 65 body of the bill fold are preferably constructed of aluminum, though it will be understood that other metal may be employed. The free edge of the plate 6 is provided with a flange 11 extending the entire length of said plate, and this flange has formed therein, intermediate of its ends, a longitudinal channel or groove 13. The free edge of the other end plate 7 of the bill fold is inwardly bent as indicated at 7' for 70 a purpose which will become apparent from the following description.

Upon the inner face of the central or body plate 5 adjacent to one edge thereof, the clamping member 14 is mounted, said member extending longitudinally of the plate. 80 Upon the end edges of the body plate 5, the angularly extending tongues 16 and 17 respectively are formed, and each of these tongues is provided upon its end with an 85 inwardly extending flange 18 and 19 respectively. To the flange 18 of the tongue 16, one end of the clamping member 14 is hingedly connected as shown at 20. The ends of the bills are adapted to be placed 90 between this clamping member and the surface of the body plate 5, and said member forced inwardly from said plate. The tongue 17 is sufficiently resilient to permit the free end of the member 14 to be forced 95 inwardly between the flange 19 on said tongue and the body plate. This flange engaging over the end of the clamping member 14 retains the same in clamping engagement with the ends of the bills. The longitudinal edge of the member 14 contiguous to the hinged edge of the plate 7 is rounded or convex as indicated at 21. The plate 7 is now folded inwardly and the bills carried with said plate over and upon the plates 5 100 and 6. The convex edge 21 of the member 15 obviates liability of tearing or mutilating the bills. The inwardly curved free edge 7' of the plate 7 is provided for a similar purpose. Thus when the other of the 105 hinged plates 6 is folded inwardly upon the plate 7, the ends of the bills are smoothly 110

folded over the curved edge 7' of said plate. The flange 11 on the plate 6 when said plate is in its closed position extends across the hingedly connected edges of the plates 5 and 7, and the projecting knuckles of the hinge 10 are received in the longitudinal groove or channel 13 provided in said flange, thus securely locking the plate 6 in its closed position and holding the bills compactly folded between the several plates.

From the foregoing, it is believed that the construction and manner of use of my improved bill fold will be clearly and fully understood. As the device is entirely constructed of metal, it will be obvious that the same is extremely strong and durable and will not show the effects of wear as is the case with the ordinary leather bill fold. As shown in Fig. 3, the outer face of the plate 6 may be provided with a monogram or otherwise ornamentally engraved.

It is to be understood that the invention may be produced in various sizes and owing to the compact arrangement of the several parts, the bill fold when closed can be readily carried in the pocket without causing the same to bulge. As the longitudinal edges of the leaves or plates are all rounded, the lining of the body will not be torn and liability of the fingers being cut in the use of the device is also avoided.

While I have shown and described the preferred construction and arrangement of the several elements employed, it will be obvious that the invention is susceptible of considerable modification without departing from the essential features or sacrificing any of the advantages thereof.

Having thus described the invention, what is claimed is:

1. A bill fold comprising a plurality of hingedly connected plates, a clamping bar hingedly mounted at one of its ends upon one of said plates and extending in parallel relation to one of the longitudinal edges of the plate and contiguous thereto, said bar having a flange over which the bills are adapted to be folded, and means to engage the free end of the clamping bar and retain the same in its clamping position.

2. A bill fold comprising a plurality of hingedly connected plates, a clamping bar hingedly mounted at one of its ends upon one of the intermediate plates and contiguous to one of the longitudinal edges thereof, the body of said bar when in its clamping

position being disposed in spaced parallel relation to the plate, said bar having a flange formed upon one of its longitudinal edges for engagement with the bills and over which the same are adapted to be folded, one of said plates being provided with means for engagement with one of the hinges whereby the plates are retained in their folded positions.

3. A bill fold comprising a plurality of hingedly connected metal plates, a clamping bar pivotally mounted at one of its ends upon one of said plates, a yieldable latch tongue carried by said plate for engagement with the free end of said bar to hold the same in clamping engagement with the bills, the other plates being movable into superposed relation to said first named plate to fold the bills upon and between said plates, and means on one of the latter plates engageable with one of the connecting hinges to retain the plates in their folded position.

4. A bill fold comprising a series of plates hingedly connected at their opposed longitudinal edges, tongues formed upon opposite ends of the intermediate plate adjacent one of its longitudinal edges, a clamping bar hingedly mounted at one of its ends upon one of said tongues, the other of said tongues being provided with a flange for engagement with the free end of the bar to hold the same in clamping engagement with the bills, the other of said plates being movable into superposed relation to said first named plate whereby the bills are folded between said plates, and means for detachably locking the plates together.

5. A bill fold comprising a series of hingedly connected plates, clamping means on the intermediate plate to clamp the ends of the bills thereto, the other of said plates being movable into superposed relation to the intermediate plate whereby the bills are folded between the plates, one of said latter plates being provided with a flange having a longitudinal groove formed therein to receive one of the connecting hinges and retain the plates in their folded position.

In testimony whereof I hereunto affix my signature in the presence of two witnesses.

JOHN A. HELLWIG.
